DENTURE CONNECTION

Original Filed Aug. 4, 1925

INVENTOR

Frank J. Kent

UNITED STATES PATENT OFFICE

FRANK J. KENT, OF MONTCLAIR, NEW JERSEY, ASSIGNOR TO CHAYES DENTAL INSTRUMENT CORPORATION, OF NEW YORK, N. Y., A CORPORATION OF DELAWARE

DENTURE CONNECTION

Application filed August 4, 1925, Serial No. 48,026. Renewed June 9, 1930.

This invention relates to removable dentures and particularly to that class of such devices in which the denture is removably held in place by a substantially T-shaped piece on one member fitting into a corresponding socket in another member. To provide a yielding interlock between these parts it has been the practice to split the head member in various ways with a view to forming a spring tongue or tongues. The metal of the head, however, is not well suited to this additional spring function, the tongues quickly losing their resiliency, breaking off and failing in other respects.

Special objects of this invention are to provide simple and practical means for resiliently holding the denture in which the above-mentioned faults will be eliminated; in which any desired spring holding tension may be provided; in which the holding tension will be of a lasting or more permanent character and of such a nature that it may be readily renewed in case of breakage or the like.

The foregoing and other desirable objects are attained in this invention by certain novel features of construction, combinations and relations of parts as set forth in the following specification.

In the drawing accompanying and forming part of this specification, the invention is illustrated in a variety of different forms, but it should be understood that the structure is capable of further modification without departure from the broad spirit and scope of the invention as hereinafter defined and claimed.

Figure 1 is a perspective view of the head member of the denture as constructed with a resilient element seated in an undercut slot in the face of the same.

Figure 2 is a similar view of the socket designed to receive the head.

Figure 3 is a similar view of the head as equipped with a reversely bent spring wire retainer.

Throughout the several views the head member is designated 12 and is shown as of generally T-shaped form and the socket member is designated 13, the latter being in the form of a shell having a cavity to receive

the cross head of the T-shaped member and a slot 14 for the neck portion of such member. These parts are usually mounted with the head piece applied to a removable denture, and the socket piece mounted in pier teeth, as well understood in the art.

In the form of the invention illustrated in Figure 1, the retainer consists of a helically coiled spring 24 held in an undercut part 25 extending diagonally across the face of the head, the coils of this spring projecting sufficiently to form a series of resilient fingers for engagement with the back wall of the socket member. A diagonal or oblique disposition of the retainer is of advantage in allowing for a greater length of retainer and in giving the retainer a hold in its seat so that it cannot pull out when the head is withdrawn from the socket.

In Figure 3 the retainer is illustrated in the form of a piece of spring wire seated in an undercut slot 26 in the face of the head and twisted alternately in four different directions to provide the bends 27 bearing against the back of the groove, the bends 28 projecting through the front of the groove and the laterally projecting oppositely projecting bends 29, 30, engaged beneath the overhanging edge portions of the groove. The projecting bends 28 make yielding contact with the socket wall and the other bends support and removably secure the retainer wire in its seat.

In the several forms of the invention, the retainers may be located diagonally of the head, as indicated in Figure 1, to increase the frictional holding effect and prevent accidental displacement of the retainer from its seat in the head member. The retainers take up most of the wear on the parts and as they are so readily renewable, any wear or breakage can be taken care of very quickly by simply substituting a new retainer. Such substitution can be made without the exercise of any special skill or the use of any special tools and may in fact be made by the user of the denture, when the occasion requires.

What is claimed is:

1. In removable dentures, the combination

of co-acting post and socket members, the post member having a relatively wide head with an open channel extending angularly thereacross and a resilient retainer held in said channel and projecting therefrom for engagement with a wall of the cooperating socket.

2. In removable dentures, the combination of co-acting post and socket members, the post member having a relatively wide head with an open channel extending angularly thereacross and a resilient retainer held in said channel and projecting therefrom for engagement with a wall of the cooperating socket, the channel being inclined with respect to the axis of the post to position the retainer obliquely of the head.

3. In removable dentures, the combination of co-acting post and socket members, the post member having a relatively wide head with an open channel extending angularly thereacross and a resilient retainer held in said channel and projecting therefrom for engagement with a wall of the cooperating socket, the channel being inclined with respect to the axis of the post to position the retainer obliquely of the head and being undercut to provide edges for holding engagement over the edges of the retainer.

4. In removable dentures, a post member having an open undercut channel across the face of the same and open at both ends and a resilient retainer entered endwise through said channel and exposed throughout its length through the open front of such channel, the channel extending across the head at an incline to the axis of the post to thereby position the retainer obliquely of the post.

5. In removable dentures, a post member having an open groove extending across the face of the same and provided with overstanding edge portions and a resilient spring wire seated in said groove, held by the overstanding edge portions and having resilient loops exposed continuously through the open front of the groove.

6. In removable dentures, a post member having a part circular groove extending across the face of the same and a coiled helical spring held in said groove with the convolutions of the same exposed through the open front of the groove.

7. In removable dentures, a post member having a part circular groove extending across the face of the same and a coiled helical spring held in said groove with the convolutions of the same exposed through the open front of the groove, said groove being inclined to the axis of the post.

In testimony whereof, I affix my signature.

FRANK J. KENT.
